UNITED STATES PATENT OFFICE.

OSCAR H. ELIEL, OF LA SALLE, ILLINOIS.

PROCESS OF MANUFACTURING METAL CASKETS.

1,412,851.

Specification of Letters Patent. Patented Apr. 18, 1922.

Application filed March 19, 1920. Serial No. 367,182.

To all whom it may concern:

Be it known that I, OSCAR H. ELIEL, a citizen of the United States, and a resident of the city of La Salle, in the county of La Salle and State of Illinois, have invented certain new and useful Improvements in a Process of Manufacturing Metal Caskets; and I do hereby declare that the following is a full, clear, and exact description of the same, reference being had to the accompanying drawings, and to the numerals of reference marked thereon, which form a part of this specification.

This invention relates to a process of manufacturing metal caskets and while the process disclosed may be applied to the manufacture of any metal container it is a process intended primarily to be used in the manufacture of burial caskets. As many such caskets are hermetically sealed to protect the body contained therein, it is particularly desirable that they be made with as few joints as possible. A multiplicity of joints in the casket construction greatly increases the difficulty of sealing air from the interior thereof and therefore increases the liability of decomposition resulting from the effect of the air. From a manufacturing standpoint it is also desirable that the caskets be made from a minimum number of pieces of stamped material. Stamping large caskets from a single sheet of metal is difficult because of the necessary drawing of the metal. It is desirable, however, to provide a casket presenting the advantages of simplicity and economy of manufacture of one which is stamped from a single sheet of metal and at the same time to avoid the difficulties encountered in the stamping process.

It is an object of this invention to provide a casket formed from two longitudinal sections of stamped metal secured in assembled relation by butt welding, brazing or other suitable means.

It is also an object of this invention to provide a method of manufacturing a casket from stamped metal sections.

It is a further object of this invention to provide a method whereby a casket may be manufactured from stamped metal sections without unduly drawing the metal in the process of stamping.

Other and further important objects of

this invention will be apparent from the disclosures in the specification and the accompanying drawings.

The invention (in a preferred form) is illustrated in the drawings and hereinafter more fully described.

On the drawings:

Figure 1 is a longitudinal view in perspective of a casket manufactured by the process of this invention.

Figure 2 is a perspective view of the bottom of a section of the casket manufactured by the process of this invention.

Figure 3 is a section on the line 3—3 of Figure 1, showing the flange removed.

As shown on the drawings:

The casket of this invention comprises in general the longitudinal portions 1 and 2 which are joined together at the longitudinal seam 3 by butt welding, brazing or in any other convenient manner. As shown in Figure 2, such portions 1 and 2 are seamless and may be conveniently stamped from a single sheet of metal without unduly drawing or tensioning the same. Flanges 5 and 6 may be integrally formed around the upper edges of said portions 1 and 2 during the stamping process and said flanges may be of any form desired to interfit with the edges of the cover of the casket. If facilities for stamping are available the entire casket may be stamped from a single piece of sheet metal with the side portions 7 and 8 thereof flaring outwardly. This latter method, however, is mainly applicable to small caskets, and the above described methods of making the caskets in longitudinal section is preferable in most cases. The method of this invention provides an economical process for the manufacture of burial caskets and caskets manufactured by this method may be readily and effectively hermetically sealed due to the minimum number of joints therein.

I am aware that numerous details of construction may be varied through a wide range without departing from the principles of this invention, and I therefore do not pur- pose limiting the patent granted otherwise than necessitated by the prior art.

I claim as my invention:

The process of making a long receptacle open at the top which consists in stamping a pair of longitudinal complementary body sec-

tions, each from a single piece of sheet material and each having at the upper edge a flange turned toward the outside of the receptacle and butt welding said sections together, whereby a joint running lengthwise of the receptacle and extending to the edges of the flanges is formed.

In testimony whereof I have hereunto subscribed my name in the presence of two subscribing witnesses.

OSCAR H. ELIEL.
